(57) **CLAIM**

The ornamental design for the figurine candle holder, as shown and described.

DESCRIPTION

FIG. 1 is a top perspective view of a figurine candle holder of the present disclosure;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a top view thereof.

The broken lines in the drawings showing the figurine candle holder illustrate the portions of the figurine candle holder that form no part of the claimed design.
